HAIR STYLIST'S ACCESSORY TABLE

Frederic V. Winkler, 14713 Waterway Drive,
Rockville, Md. 20853

Filed Sept. 21, 1971, Ser. No. 182,574

Term of patent 14 years

Int. Cl. D6—03

U.S. Cl. D6—25

Fig. 1

Fig. 2

Fig. 3

Fig. 4

FIG. 1 is a perspective view of a hair stylist's accessory table showing my design;

FIG. 2 is an end elevational view of the hair stylist's accessory table shown in FIG. 1;

FIG. 3 is a side elevational view of the hair stylist's accessory table shown in FIG. 2, and

FIG. 4 is a top plan view of the invention shown in FIGS. 1, 2 and 3.

I claim:

The ornamental design for a hair stylist's accessory table, as shown.
